UNITED STATES PATENT OFFICE.

REISSUED

HENRY L. PALMER, OF STILLWATER, NEW YORK.

IMPROVEMENT IN THE MANUFACTURE OF PASTEBOARD.

Specification forming part of Letters Patent No. 87,359, dated March 2, 1869.

To all whom it may concern:

Be it known that I, HENRY L. PALMER, of Stillwater, Saratoga county, State of New York, have invented a new and useful invention for the purpose of uniting paper to what is known in trade and mechanical uses as pasteboard, whether made of straw or other materials, of which the following is a specification:

The usual preliminary work of box-making is first to cover one side of the sheets of pasteboard to be used with paper, usually white, this being when the box is completed the inside lining of it.

This work is now done by hand. The paper is used in sheets. The drying is accomplished by exposure to the atmosphere, and the work, when done, is liable to warp, and to be rough and uneven.

I propose to save by this invention this hand manipulation, with an economy in the cost of paper and labor, and with the production of the material in a superior condition.

I do hereby declare that the following is a true and full description of the construction and operation of the invention, reference being had to the annexed drawings making part of this specification.

Figure 1 is a view of the whole machine or combination. Fig. 2 is an end view of the part relating more particularly to the operation of pasting and uniting the pasteboard and paper.

Fig. 1, A is a paste-reservoir; B, a concave roller revolving in it, and giving the paste to C, a convex roller revolving on its own periphery, and resting on rollers B and D. D is a concave roller, used for the purpose of bringing the paper against the pasting-roller C, and also for pressing the paper and pasteboard together at the point of contact between D and L, and also with L to give a convex surface to the pasteboard to which the paper is applied. L is a convex roller; M, a spring under the bearings of L, to accommodate the pressure of the rollers D and L to varying thicknesses of pasteboard. F is an endless belt, by which the pasteboard is carried to the point of contact with the paper, and by which the materials, when united, are carried

in the direction indicated by the arrows around the drying-cylinders and to the calenders. G G' are cylindrical rollers, the uses of which are illustrated in Fig. 2. H is a drying-cylinder; I and I', calenders. K and K' are knives. The drying-cylinder, calender, and knives are intended to represent such as are usually used in paper-mills for an equivalent purpose.

Fig. 2, C is a pasting-roller; E, the roll of paper leading in the direction of the dotted lines; D, a roller; L, a pressing-roller and also a guide-roller for the felt; M, a spring under the bearings of L.

If it be desired to paste the board instead of the paper, it will be done by changing the direction of the paper, and, as in the figure, bring it directly from E to G G', as indicated by the dotted lines, the pasteboard coming from between rollers D and L, as indicated by the round dotted line, where it has been pasted, meets the paper between G G', after which it will proceed as in Fig. 1.

I do not confine myself to the use of concave and convex rollers D, L, C, and B, but can use cylindrical in their place.

Operation: As the paper leaves the roll E in Fig. 1 it proceeds in the direction of the dotted lines between rollers D and C, receiving the paste by coming in contact with the latter roller. It then passes to the under side of D. The pasteboard is fed in sheets and carried forward by the belt F to the under side of the roller D, where it meets the paper. The two materials are then passed through with the felt between rollers D and L, the spring M accommodating for any difference there may be in the thickness of the pasteboard or paper. The object of the concave and convex rollers is seen at this point by giving a rounding or convex form to the surface to which the paper is applied, to compensate for any contraction of the wet paper. The material then passes forward in the direction indicated by the arrows between rollers G G', where it receives additional pressure around the drying-cylinder H, where it is dried, thence through the calenders I I', where it is smoothed and straightened, thence between the knives K K', which will sever the sheets, or cut to any desired size.

I do not claim as my invention the drying-

cylinders H, calenders I I', knives K K', but their use in combination with the other parts, as described.

What I claim as my invention, and desire to secure by Letters Patent, is—

1. The method of uniting a continuous sheet of paper to sheets of pasteboard, as herein described.

2. Giving a convex form to the pasteboard at the line where the pasteboard and paper meet, by means of convex roller L and concave roller D or their equivalents, for the purpose specified, substantially as described.

3. The combination of trough A, rollers B, C, D, and L, roller E, or its equivalent, for hold-

ing the continuous sheet of paper, rollers G G', and endless apron F or its equivalent, for the purpose specified, substantially as described.

4. The combination of trough A, rollers B, C, D, and L, roller E, spring M, and endless apron F, or its equivalent, for the purpose specified, substantially as described.

5. The combination of trough A, rollers B, C, D, and L, apron F, roller E with a drying-cylinder, substantially as described.

HENRY L. PALMER.
